UNITED STATES PATENT OFFICE.

PAUL R. JORDAN, OF INDIANAPOLIS, INDIANA.

EXHAUST VENTILATOR.

Application filed February 15, 1926. Serial No. 88,403.

This invention relates to the ventilation of buildings, especially those of the larger class, such as school buildings, and has reference more particularly to an appliance that is designed for controlling and regulating outflow of air from buildings under the influence of air currents passing over the tops of the buildings.

An object of the invention is to provide an improved exhaust ventilator appliance which shall be of such construction as to be adapted to be readily applied to the top of an air-duct, and which shall be adapted to afford the advantages without entailing the disadvantages of rotary ventilator appliances.

Another object is to provide an improved ventilator appliance which shall be mainly stationary with internal co-operating valves constructed and arranged to enable the appliance to operate efficiently under the controlling influence of atmospheric air currents, equally as well with shifting currents as with constant currents.

A further object is to provide an improved exhaust ventilator appliance which shall be of such construction as to be of simple design permitting low cost of manufacture, and which shall be highly efficient, durable and reliable, noiseless in operation and economical in use, and also have a pleasing appearance.

With the above-mentioned and other objects in view, the invention consists in an exhaust ventilator appliance of novel construction generally, including novel valves and mounting thereof; the invention consisting also further in the novel parts and combinations and arrangements of parts as hereinafter particularly described and further defined in the appended claims.

Referring to the drawings, Figure 1 is a vertical central section of the ventilator appliance in which the valves thereof are free to act; Fig. 2 is a fragmentary vertical central section of the appliance in which the valves are restrained from action and held in closed position to operate as a damper; Fig. 3 is a fragmentary horizontal section in proximity to the top of the structure and broken away on different planes to expose lower parts; Fig. 4 is an elevation view of the appliance on a reduced scale; and Fig. 5 is a top plan of the appliance on a further reduced scale.

Similar reference characters in the different figures of the drawings indicate corresponding elements or features of construction herein referred to in detail.

In the drawings the numeral 1 indicates the roof of a building and 2 the terminal portion of an air-duct extending through the roof from the interior of the building.

The improved ventilator appliance comprises a neck 3 adapted to be connected with the top of the air-duct, the neck or at least the upper portion thereof being rectangular in cross-section, the housing part of the appliance preferably being rectangular in plan so as to permit economical manufacture. The housing has a plurality of apertures in its side portions, preferably four in number, and accordingly the housing is provided with a bottom or floor comprising four inclined sections 4, 4^a, 4^b, 4^c, the sections being connected to the top of the neck 3 and extending outwardly and downwardly therefrom. Four vertical partitions 5, 5^a, 5^b, 5^c, are connected to the bottom or floor on the lines of junction of the sections thereof, to direct air currents into the housing. In some cases corner posts 6 and 6' are secured to the outer edges of the partitions to stiffen them and constitute facing members, being connected with flanges 7 formed on the bottom sections. A pyramidal roof 8 is secured to the tops of the partitions and preferably has a downwardly extending face flange 9 connected with the corner posts. The upper portion of each bottom section has an outwardly facing valve seat member 10 thereon which is connected structurally to the neck 3, defining the bottom of the apertures, the seat member being adapted for preventing flow of rain water into the neck. At the opposite ends of each seat member 10 the adjacent partitions have valve seat members 11 and 12 fixed thereto respectively that are preferably inclined so as to extend outwardly from the ends of the seat members 10. A suitable distance above the seat member 10 the partitions are provided with oppositely arranged pivot supports 13 and 14, other partitions having similar supports 13' and 14', there being a pair of supports at the top line of each aperture or throat at the inner ends of the partitions, the space between each two partitions affording a mouth channel to direct air currents to the valve

and permitting outlet of air past the valve when open.

Each ventilator valve comprises a horizontal fulcrum portion 15 provided at its ends 5 with pivot pins or trunnions 16 and 17 that are supported in the pivot supports 13 and 14 respectively, a valve plate 18 extending downwardly and outwardly from the fulcrum portion and a valve plate 19 extending 10 downwardly from the plate 18 to cooperate with the valve seat members. When the valve is open the plate 19, being angular relatively to the plate 18 extends slightly outwardly at an inclination opposite to that 15 of the valve seat and its lower end has a water-shed flange 20 projecting outwardly, and the back of the plate 19 has a felt packing 21 thereon to insure tight contact with the valve seat members and to deaden 20 sound that may be caused by the valve when closing against the seat. Each valve has also a tapered lever plate 22 extending upward from the fulcrum portion, and the top of the lever plate has a relatively angular 25 balancing plate 23 extending inwardly towards the middle of the housing and preferably is provided with a weight element 24 to counter-balance the valve so as to normally hold the valve in open position yet 30 permitting it to be closed by slight external air-pressure. Above the pivot supports in each mouth channel the opposite partitions are provided with two wings 25 and 26 respectively against the backs of which the 35 lever plate 22 comes into contact when the valve is closed which with the valve plates entirely close the adjacent apertures in a side of the housing. A suitable number of stop bars 27 are secured to the top of the 40 roof 8 to limit the opening movement of the valves.

In order to cheaply provide a damper to close or regulate the ventilator a lift plate 45 is provided and arranged below the ends of the balancing plate 23 that operate as lever members, and the lifting plate may be variously supported and operated, preferably by means of two cables 29 and 30 connected at one end to the lifting plate and 50 extending over pulleys 31 suitably supported by the roof 8, the cables extending from the pulleys downward through suitable openings in the lift plate and to a counterweight 32 to which the cables are secured, the counter- 55 weight being adapted by the force of gravity to pull up the lifting plate into engagement with the plates 23 and to push them up so as to close the valves. A chain 33 is connected to the lifting plate and extends downward 60 through the counterweight whereby to pull the lifting plate downward more or less and permit normal operation of the valves either fully or to any desired degree. The chain is provided at its lower end with suitable 65 means for fastening it in proper position;

such as a hook 34 attached to the chain which may be connected to any suitably arranged anchorage.

In practical use, the ventilator housing being stationary, an air-current coming from 70 such direction as to enter one of the mouth channels, creates air-pressure on the plates 18 and 19 of the valve therein, exerting force also on the flange 20 and forces the valve against its seat. In case the air-current 75 moves so as to enter two adjacent mouth channels, the valves in both channels are closed by the air-pressure against the action of the counterweights of the valves. The valves in the opposite side of the housing are 80 automatically opened by their counterweights under normal conditions and permit outflow of air through the housing, the outflow obviously being accelerated because of suction produced by atmospheric air-currents flowing past the ventilator which tend to create vacuum in the housing through the rearward open valve. When conditions make it desirable to use the ventilator damper the chain 33 is released and consequently the 85 lifting plate 28 is drawn upward into engagement with all the plates 23, resulting in the shifting of the valves to closed position or so as to be nearly closed to permit limited 90 degree of ventilation. 95

What is claimed as new is:

1. An exhaust ventilator including a pyramidal bottom having a quadrangular opening therein, the upper portion of the bottom having outward-facing valve seats thereon, a neck connected to the upper portion of said bottom, four partitions secured radially upon said bottom, a roof secured to the tops of the partitions, and four valves pivotally supported above the valve seats respectively, by 100 the partitions and movable by external air-pressure to the seats.

2. An exhaust ventilator comprising a hollow neck, a floor comprising four inclined sections secured at their upper portions to 110 the neck and having outward-facing valve seats on their tops, four upright partitions radially secured to the floor at the junctions of the sections thereof, a roof secured to the tops of the partitions, four valves pivotally supported above the valve seats respectively to co-operate with the seats in response to external air-pressure, each valve having a counterbalanced lever normally operating to open the valve, a pulley supported by the 115 roof, a cable movably supported by the pulley, a lifting plate arranged below the valve levers and secured to one end of the cable, a weight element arranged below the lifting plate and secured to the opposite end of the 120 cable and adapted to lift the plate and thereby raise all the levers to close the valves, and a pull-chain connected to the lifting plate and provided with means to anchor it. 125

3. In an exhaust ventilator, the combina- 130

tion of a housing comprising a pyramidal bottom having a quadrangular opening therein, the upper portion of the bottom having outward-facing valve seats thereon, 5 four partitions secured radially upon said bottom, a pyramidal roof secured to the tops of the partitions; and four valves arranged each between two of the partitions, each valve comprising a horizontal fulcrum portion provided at its ends with pivot pins that are supported on the two partitions, a valve

plate extending downwardly and outwardly from the fulcrum portion and having a relatively angular portion to co-operate with the adjacent one of the valve seats, and a tapered 15 lever plate extending upward from said fulcrum portion and having a relatively angular balancing plate.

In testimony whereof, I affix my signature on the 12th day of February, 1926.

PAUL R. JORDAN.
